UNITED STATES PATENT OFFICE.

CHARLES C. WHITE, OF CHICAGO, ILLINOIS.

DESIGN FOR A DRESSING TABLE.

Application filed December 12, 1921. Serial No. 521,936. Term of patent 14 years.

To all whom it may concern:

Be it known that I, CHARLES C. WHITE, a citizen of the United States, residing at Chicago, in the county of Cook and State of Illinois, have invented a new, original, and ornamental Design for Dressing Tables, of which the following is a specification, reference being had to the accompanying drawing, forming a part thereof.

The drawing is a perspective of a dressing table showing my new design.

I claim:

The ornamental design for a dressing table, as shown.

CHAS. C. WHITE.
